(57) **CLAIM**

We claim the ornamental design for the headset for measuring brain waves, as shown and described.

DESCRIPTION

FIG. 1 is the front perspective view of the headset for measuring brain waves showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof;

FIG. 7 is the bottom plan view thereof;

FIG. 8 is the partially enlarged view of FIG. 1; and,

FIG. 9 is the bottom perspective view thereof.

The broken lines in the drawing show unclaimed environment only and form no part of the claimed design.

The dot-dash broken lines encircling portions of the claimed design that are illustrated in enlargements form no part of the claimed design.
